STILT

William Owen, Dallas, Tex.

Application December 1, 1948, Serial No. 149,915

Term of patent 14 years

(Cl. D34—14)

To all whom it may concern:

Be it known that I, William Owen, a citizen of the United States of America, residing at Dallas, county of Dallas, and State of Texas, have invented a new, original, and ornamental Design for a Stilt, of which the following is a specification, reference being had to the accompanying drawing, forming a part thereof wherein:

Figure 1 is a view in side elevation of a stilt embodying my new design. The dotted lines shown in Figure 1 are for illustrative purposes only;

Figure 2 is a top plan view of the stilt, and

Figure 3 is a view in rear elevation of the stilt.

I claim:

The ornamental design for a stilt, as shown and described.

WILLIAM OWEN.
